UNITED STATES PATENT OFFICE.

JOSEPH MARTIN, OF NEW YORK, N. Y., ASSIGNOR TO UNITED STATES CABINET BED CO., OF NEW YORK, N. Y., A CORPORATION OF NEW YORK.

COMBINATION SINGLE AND DOUBLE COUCH BED.

Application filed October 18, 1927. Serial No. 226,832.

This invention relates to combination single and double couch beds such as illustrated in my copending application Ser. No. 189,026 filed May 5, 1927.

5 Among the objects of the present invention it is aimed to provide an improved combination single and double couch bed whereby the extent of vertical movement of the main bed section is sufficient to provide an extended or 10 enlarged compartment for bed clothes or the like when the couch bed is in single bed formation.

The present invention also aims to provide an improved construction to prevent the locking or hitching of the bed sections so that the 15 couch bed may be opened or closed with facility.

These and other features, capabilities and 20 advantages of the invention will appear from the subjoined detailed description of one specific embodiment thereof illustrated in the accompanying drawings in which

Figure 1 is an end elevation showing the bed sections in single bed formation with the 25 spring mattresses removed;

Fig. 2 is a fragmental end elevation showing the respective positions of the bed sections when the extensible bed section has been raised in the course of opening the couch bed;

30 Fig. 3 is an end elevation of the bed sections in double bed formation with the spring mattresses removed;

Fig. 4 is a fragmental plan of the bed sections in double bed formation with the spring 35 mattresses removed;

Fig. 5 is a section on the line 5—5 of Fig. 1; Fig. 6 is a section of the line 6—6 of Fig. 2.

In the embodiment illustrated the main frame is illustrated as consisting of corner standards 1—2 at both ends of the same which are connected to one another by the end bars 40 3 and 4 and by the side bars 5 and 6.

In the main frame, the bed sections A and B are adapted to nest in single bed formation. 45 In double bed formation the section A is adapted to be positioned in a raised position in the main frame, and the bed section B adapted to be positioned substantially in alignment with the bed section A and to one 50 side of the main frame.

The main frame C is provided with two cross bars 3 one at each end, and each of these cross bars has pivotally connected thereto a pair of bent levers 7 and 8. The levers 7 and 55 8 of each pair are substantially identical hav-

ing short arms 9 and 10 and long arms 11 and 12 respectively. The levers 7 and 8, are pivotally connected to the rail 3 at the intersection of the arms to wit at the points 13 and 14. The points 13 and 14 are spaced from one another and from the standard 2 a short distance. The free ends of the levers 7 and 8 are pivotally connected to the cross bar 15 of the bed section B at the points 16 and 17 which are spaced from one another a distance 60 equal to the distance between the points 13 and 14. The free ends of the arms 9 and 10 are pivotally connected to the short links 18 and 19 respectively which are pivotally connected to the cross bar 20 of the bed section A 65 at the points 21 and 22. The pivot points 21 and 22 are spaced from one another a distance equal to the distance between the pivot points 13 and 14. Since both ends of the bed 70 are similar, to facilitate description but one end, the near end, illustrated, will be described, it being understood that both ends 75 of the bed are substantially identical.

As shown the levers 7 and 8 are preferably pivoted to the inner face of the rail 3, the arms 9 and 10 are pivoted to the outer face of the links 18 and 19, and the links 18 and 19 are pivoted to the outer face of the end bar 20. The arms 9 and 10 are bent inwardly at 23 and 24, see particularly Fig. 4 to afford 80 clearance for the control lever 25 which has the right hand end pivoted to the inner face of the corner standard 2, and its left hand end pivoted to the outer face of the rail 20. The control lever 25 is bent outwardly at 26, 85 see particularly Fig. 4, to cooperate with the bends 23 and 24 to afford clearance for the control lever 25. The control lever 25 is also downwardly bent at 27 to cooperate with the bends 26, 23 and 24 to afford clearance for 90 the control lever 25. To facilitate the operation of the bed sections into single and double bed formation, springs are provided in the usual way to wit the springs 28 and 29, the spring 28 being pivotally connected to the link 30 which is pivotally connected to the outer face of the corner standard 1. The right hand end of the spring 28 is connected to the pin 31 extending outwardly from the lever 7. The left hand end of the spring 29 100 is connected to the pin 31 and is connected at its right hand end to the link 32 extending from the outer face of the rail 3.

To facilitate the operation of both ends of 105 the bed simultaneously, the free ends of the 110

arms 11 of the levers 7 are preferably fixed to the rocker shaft 33, which shaft 33 is pivotally connected to the end bar 15 of the bed section B and extends through such bar 15 terminating in an angular head which is riveted or otherwise fixed to the free ends of the arms 11, see particularly Figs. 3 and 4.

The bed section B in the present instance is provided with a rigid leg member 35 extending downwardly from the end bar 15.

With the present improvement the links 18 and 19 are considerably shorter than the arms 9 and 10 of the levers 7 and 8 and by their cooperation with the control lever 25 it is possible to depress the bed section A as low as possible preferably to a point a little above the floor so that a maximum extent of movement of the bed section A may be effected. Furthermore with the right hand end of the control lever 25 pivoted midway between the lowest and highest positions of the bed section A, the arc of movement of the left hand end of the lever 25, and therefore of the bed section A will be but slight, and thus confine the bed section A to a minimum amount of lateral movement.

The pivoted points connecting the arms 9 and 10 with the links 18 and 19, to wit the pivot pins 36 and 37 have inwardly extending projections 38 and 39 which form stops to engage the lower face of the end rail 20 to limit the downward movement of the bed section A, and on the other hand to prevent the links 18 and 19 bending down below an imaginary dead center where it would be impossible to raise the bed section A, by the mere manipulation of the bed section B.

The pivot points 21 and 22, see particularly Figs. 2 and 6 are provided with outwardly extending lugs 40 and 41. The lugs 40 and 41, see particularly Fig. 2 cooperate with the arms 9 and 10 to prevent the arms 9 and 10 swinging across the pivot points 21 and 22, when the bed section A is being swung upwardly and thus prevent the links 18 and 19 causing a jamming action with the main control lever 25 and the arms 9 and 10.

It is obvious that various changes and modifications may be made to the details of construction without departing from the general spirit of the invention as set forth in the appended claims.

I claim:

1. The combination with a frame, of a main bed section movable in an up and down direction, an extension bed section, a control mechanism at each end of said frame for simultaneously operating said bed sections, each control mechanism comprising a pair of bent levers and a pair of links, the bent levers being pivotally connected to said frame and having short and long arms, the ends of the long arms being pivotally connected to said extension bed section, the links connecting the main bed section with the short arms of

said bent levers, means for controlling the main bed section in its up and down movement relative to said frame, and stops on said links cooperating with said main bed section to limit its downward movement.

2. The combination with a frame, of a main bed section movable in an up and down direction, an extension bed section, a control mechanism at each end of said frame for simultaneously operating said bed sections, each control mechanism comprising a pair of bent levers and a pair of links, the bent levers being pivotally connected to said frame and having short and long arms, the ends of the long arms being pivotally connected to said extension bed section, the links connecting the main bed section with the short arms of said bent levers, means for controlling the main bed section in its up and down movement relative to said frame, and stops on said links cooperating with the short arms of said bent levers to prevent jamming.

3. The combination with a frame, of a main bed section movable in an up and down direction, an extension bed section, a control mechanism at each end of said frame for simultaneously operating said bed sections, each control mechanism comprising a pair of bent levers and a pair of links, the bent levers being pivotally connected to said frame and having short and long arms, the ends of the long arms being pivotally connected to said extension bed section, the links connecting the main bed section with the short arms of said bent levers, means for controlling the main bed section in its up and down movement relative to said frame, and two sets of stops on said links, one set cooperating with the main bed section to limit its downward movement and the other set cooperating with the short arms of said bent levers to prevent jamming.

4. The combination with a frame, of a main bed section movable in an up and down direction, an extension bed section, a control mechanism at each end of said frame for simultaneously operating said bed sections, each control mechanism comprising a pair of bent levers and a pair of links, the bent levers being pivotally connected to said frame and having short and long arms, the ends of the long arms being pivotally connected to said extension bed section, the links connecting the main bed section with the short arms of said bent levers, and a control link pivotally connected at one end to said frame and at its other end to said main bed section to control said main bed section in its up and down movement relative to said frame, the links being shorter than the short arms of said bent levers.

5. The combination with a frame, of a main bed section movable in an up and down direction, an extension bed section, a control mechanism at each end of said frame for simultaneously operating said bed sections, each control mechanism comprising a pair of bent levers and a pair of links, the bent levers being pivotally connected to said frame and having short and long arms, the ends of the long arms being pivotally connected to said extension bed section, the links connecting the main bed section with the short arms of

- tanously operating said bed sections, each control mechanism comprising a pair of bent levers and a pair of links, the bent levers being pivotally connected to said frame and 5 having short and long arms, the free ends of the long arms being pivotally connected to said extension bed section, the links connecting the main bed section with the short arms of said bent levers, and a control link pivotal- 10 ly connected at one end to a point on said frame midway between the lowest and highest position of said main bed section and at its other end to said main bed section, to reduce to a minimum the lateral movement 15 of said main bed section when swung into double bed formation.
6. The combination with a frame, of a main bed section movable in an up and down direction, an extension bed section, a control 20 mechanism at each end of said frame for simultaneously operating said bed sections, each control mechanism comprising a pair of bent levers and a pair of links, the bent levers being pivotally connected to said frame and 25 having short and long arms, the ends of the long arms being pivotally connected to said extension bed section, the links connecting the main bed section with the short arms of said bent levers, and a control link pivotal- 30 ly connected at one end to said frame adjacent to the extension bed section when swung into double bed formation at a point midway between the lowest and highest posi-

tions of said main bed section, the other end of said control link being pivotally connected 35 to the end of said main bed section remote from said extension bed section when swung into double bed formation thereby to reduce to a minimum the amount of lateral movement of said main bed section when swung 40 into double bed formation.

7. The combination with a frame, of a main bed section movable in an up and down direction, an extension bed section, a control 45 mechanism at each end of said frame for simultaneously operating said bed sections, each control mechanism comprising a pair of bent levers and a pair of links, the bent levers being pivotally connected to said frame and 50 having short and long arms, the free ends of the long arms being pivotally connected to said extension bed section, the links connecting the main bed section with the short arms of said bent levers, and a control link pivotal- 55 ly connected at one end to a point on said frame midway between the lowest and highest position of said main bed section and at its other end to said main bed section, to reduce to a minimum the lateral movement 60 of said main bed section when swung into double bed formation, the control link and the bent levers being bent so that the control link will clear said pair of links and bent levers when the device is swung into and out of double bed formation.

JOSEPH MARTIN.
